UNITED STATES PATENT OFFICE.

MORRIS L. BAYARD AND MINOR HARVEY, OF PHILADELPHIA, PENNSYLVANIA.

FILTER-SAND-CLEANING MACHINE.

Application filed March 23, 1928. Serial No. 264,060.

Our invention relates to a new and useful filter sand washing machine adapted for use on large filter beds in water works and similar establishments whereby the sludge, 5 scum, vegetation, bacteria and other foreign matter habitually forming, depositing and accumulating on the sand of filter beds may be removed without the necessity of removing the filter sand from its bed or in any way 10 interfering with or interrupting the function or use of the filter bed as a whole.

Our invention further relates to a filter sand washing machine of this general character which is mounted on a self-propelled 15 floating vessel such as a boat, barge or the like, which is adapted to travel or float in the water over the bed of sand to be washed and cleaned, thus eliminating the necessity of completely or partially draining the water from the filter bed which has heretofore 20 generally been necessary when it was desired to wash the filter sand.

Our invention further relates to a sand washing machine, which while operated by 25 the same source of power which propels the supporting vessel, may nevertheless be operated at various speeds or stopped completely irrespective of the propulsion of said supporting vessel.

30 Our invention further relates to a novel construction of the washing nozzles on the head of our novel sand washing machine, whereby the sand is thoroughly agitated and washed, in less time and at less expense and effort.

Our invention further relates to various other advantages sought to be attained by our novel construction, all of which will 35 hereinafter be described.

40 To the above ends our invention consists of a boat or similar self-propelled floating vessel, means for propelling the latter, a head adjustably carried by said boat, washing nozzles at the lower end of said head for piercing and agitating the sand and injecting water thereinto, means for supplying water to said nozzles and means for sucking and withdrawing the water accumulating in 45 said head.

50 Our invention further consists in a novel construction of a filter sand washing machine which may be operated at any desired speed regardless of the speed or propulsion of the supporting boat or vessel and which 55 may be adjusted to suit the thickness and grade of sand used in different filter beds.

Our invention further consists of various other novel features of construction and advantage hereinafter described and claimed.

For the purpose of illustrating our invention we have shown in the accompanying drawings one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of the instrumentalities as herein shown and described.

In the accompanying drawings,

Figure 1, represents a vertical sectional view of a filter sand washing machine embodying our invention the section being on 75 line 1—1 of Figure 2.

Figure 2, represents a top, plan view of the filter sand washing machine seen in Figure 1.

Figure 3, represents, on an enlarged scale, 80 a fragmentary view in side elevation of one of the propellers shown in the left hand portion of Figures 1 and 2.

Figure 4, represents on an enlarged scale 85 a side elevation partly in section showing details of the construction shown in the right hand portion of Figure 1.

Figure 5, represents on an enlarged scale, 90 a sectional view of the central nozzle shown in Figure 6, the section being taken on line 5—5 of Figure 6.

Figure 6, represents a top, plan view of the assembly of nozzles employed, one of which is shown in detail in Figure 5.

Figure 7, represents, on an enlarged scale, 95 a perspective view of the adjustable head forming part of our invention, and seen in the right hand portion of Figures 1 and 4.

Referring to the drawings, in which like reference characters indicate like parts, 1 100 designates a boat, barge, or any other self-propelled floating vehicle, on which my novel filter sand washing machine may be mounted, the boat being driven or propelled by an engine or motor 2 of any suitable, conventional design. The engine 2 is provided with the drive shaft 3 which has the gear 4 fast thereon which meshes with the pinions 5 fast on the shafts 6 journaled in the bearings 7 carried by the frame 8, which in turn 110 is carried by or integral with the casing of the engine 2. The shafts 6 carry at their

free ends the pulleys 9, over which pass the sprocket chains 10 passing over the pulleys 11 fast on the propeller shafts 12, which carry at their outer ends the propellers 13 which are fast on the arms 14 which are pivoted to the head 15 as at 16, said head being fast on the shaft 12. The arms 14 are pivoted at the rear ends 17 to the bifurcations 18 of the sliding sleeve 19, which is adapted to telescope or slide over the shaft 12 and which is connected at its rear end to the clutch mechanism 20 which is operated by the lever 21 to vary the angular position of the propeller blades 13. Thus, if it is necessary to stop the boat 1 entirely, the sliding sleeve 19 is adjusted by means of the clutch lever 21 to bring the propeller blades 13 into a vertical "neutral" position, (where the revolution of said blades will not propel the boat 1) thus completely arresting the movement of the boat without stopping the engine 2. The clutch mechanism 20 in conjunction with the sliding sleeve 19 also serves to regulate the speed and direction of travel of the boat, since, by varying the angle or inclination of the propeller blades 13 with respect to the vertical, the resistance encountered by the operative surface of the propellers is varied and the speed and direction of the boat are varied at will. It is obvious that other forms of propelling mechanism can be employed if desired. The main drive shaft 3, operating the propeller shafts 12, extends through the frame 8 and operates the suction pump 22 of any suitable construction, said pump being provided with the discharge hose 23 leading to a point of disposal on the main land. The suction pump 22 is also provided with the suction hose 24 leading from the chamber 25 in the head 26, which will be hereinafter described. Simultaneously with the operation of the suction pump 22, the main drive shaft 3 also operates the force pump 27, which is provided with the suction inlet 28 communicating with the water in which the vessel 1 is floating and the discharge 29 leading to the discharge nozzles and their adjuncts in the chamber 25. The head 26 is of a generally inverted cup shape and is composed of the vertical parallel walls 30 having the upturned bottom peripheral flange 31, which serves to smoothen out the sand in front of and behind the head 26, and has the top wall 32 to which are secured the uprights 33, joined at their upper ends by the transverse beam 34. The uprights 33 carry the lower sheaves 35 around which pass the chains or connections 36, the ends of which are secured to the boat as at 37 and the other ends of which are wound around the drums 38, provided with the handles 39, and adapted to raise and lower the head 26 and its adjuncts to suit varying depths of the water and sand being washed. Through

the transverse beam 34* which is mounted on the uprights 33* secured to the top wall 32 of the head 26 extends the threaded adjusting rod 41, which is provided at its upper end with the manually operated hand wheel 42. The lower end of the rod 41 passes through the top wall 32 of the head 26 and is secured to the transverse bar 43 to the ends of which are secured the brackets 44, to the rear ends of which latter is secured the transverse tubular member 45 which carries the series of nozzles 46 and the central nozzle 49 and which is provided with the upper port 47 and the bottom, elongated port 48. The central nozzle 49 is provided with the nipple or integral upper extension 50, which is connected by the hose 53 to the connection 51 of the discharge pipe 29 of the force pump 27. The transverse, tubular member 45 is closed at its ends and is pivoted in the brackets 52 which are secured to the rear wall of the head 26. By manipulating the hand wheel 42 to raise or lower the transverse bar 43, the angular disposition or inclination of the series or row of nozzles 46, including the central nozzle 49, is regulated with respect to the sand bed 55.

The operation is as follows: The boat 1 is launched in the water of the filter bed and the head 26 is lowered until the upturned flange 31 thereof just touches the surface of the filter sand bed. Water is then pumped by the force pump 27 through the discharge hose 29, the connection 51, coupling hose 53 and nipple 50 of the central nozzle 49, into the tubular member 45 through the upper port 47 therein. The water flows from the tube 45 through the lower elongated ports 48 into the respective nozzles 46 which are buried in or are ploughing through the sand bed 55, the inclination or angular disposition of said nozzles being regulated by the manipulation of the hand wheel 42 and its adjuncts as above set forth. The travel of the nozzles 46 and the nozzles 49 through the sand bed, as well as the force of the water forced therethrough by the pump 27, agitates the sand and washes it, by separating therefrom the scum, vegetation, bacteria and other impurities which are now floating within the chamber 25 of the head 26, said chamber being isolated from the rest of the water in the filter bed, as will be apparent. The dirty water resulting from the washing of the particular area of sand covered by the head 26 and acted upon by the nozzles 46 is sucked through the suction inlet 58 in the direction of the arrow through the suction hose 24, by means of the suction pump 22 and is discharged through the discharge 23 into a sewer or the like outside of the filter bed. The boat is then moved and another area is thus washed, it being understood that the process of washing may be carried on continuously and simultane-

ously with the travel of the boat or independently thereof.

The water employed in washing the sand under, or enclosed within the head 26 at any given time is drawn by the force pump 27 through the suction inlet 28 in the direction of the arrow, from the water in the filter bed. The upturned flange 31 on the bottom of the head 26 serves to smoothen out the sand before the approach of the nozzles 46 and after their passage over the sand being washed, thus facilitating the travel of the nozzles and their adjuncts and insuring thorough uniformity of depth and consequently of the effectiveness of the apparatus.

By making the bodies of the nozzles 46 and 49 of a generally curved or concaved contour, the water pumped therethrough into the sand bed is given impetus in an upward direction, and instead of tending to force its way down through the sand bed into the reservoir of pure filtered water, it will, after separating the impurities from the sand, travel in a generally upward direction towards the surface of the sand carrying all impurities with it, and finally accumulates together with the impurities from the sand in the chamber 25 of the head 26 to be withdrawn through the suction inlet 58, the pipe 24 and their adjuncts to a suitable point of disposal outside of the filter bed. By adjusting the height of the head 26 by means of the drum 38 and its adjuncts, and by regulating the angular position of the nozzles 36, our novel apparatus is rendered universally applicable and efficient.

By our novel construction we further provide for the accurate timing of the speed of the boat 1 and the operation of the washing head 26, to the end that the boat is propelled at a rate which will permit of the thorough washing of the sand covered by the chamber 25 in the time required for traveling over such area, thus resulting in a continuous, uninterrupted process.

It will be seen from Figures 4 and 6 that the uprights 33 are provided with the guide rollers 59 which bear against the walls 60 to reduce friction and facilitate the raising and lowering of the head 26 and its adjuncts, as will be apparent. The connection 51 of the discharge hose 29 passes through the sleeve 62 in the top wall 32 of the head 26 while the intake 58 of the suction hose 24 passes through an extension 63 of said sleeve 62. Similarly the lower portion of the stem 41 passes through the sleeve 64 in the top 32 of the head 26 while its upper threaded portion extends through the internally threaded sleeve 65 in the upper transverse beam 34, as will be understood from Figure 4.

We are aware that the invention may be embodied in other specific forms without de-

parting from the spirit or essential attributes thereof, and we therefore desire the present embodiment to be considered in all respects as illustrative and not restrictive, reference being had to the appended claims 70 rather than to the foregoing description to indicate the scope of the invention.

Having thus described our invention what we claim as new and desire to secure by Letters Patent, is:—

1. In a device of the character stated, an inverted cup shaped head, an apertured tube rotatably mounted therein, arms projecting from the ends of said tube, a transverse rod joining the outer ends of said arms, a vertically adjustable stem having its lower end secured to said rod, a series of nozzles secured to said apertured tube, a discharge pipe for leading water into said tube and nozzles and a suction pipe extending into 85 the upper portion of said head for withdrawing water and impurities from said head.

2. In a device of the character stated, a vertically adjustable inverted cup shaped head, an oppositely apertured tube rotatably 90 mounted therein, arms projecting from the ends of said tubes, a transverse rod joining the outer ends of said arms, a vertically adjustable stem having its lower end secured to said rod, a series of curved nozzles secured 95 to said apertured tube, a discharge pipe for leading water into said tube and nozzles and a suction pipe communicating with the upper portion of said head for withdrawing the water and impurities from said head. 100

3. In a device of the character stated, an inverted cup shaped head, an apertured tube rotatably mounted therein, arms projecting from the ends of said tube, a transverse rod joining the outer ends of said arms, a vertically adjustable stem having its lower end secured to said rod, a series of nozzles secured to said apertured tube, a discharge pipe for leading water into said tube and nozzles and a suction pipe extending into 110 the upper portion of said head for withdrawing water and impurities from said head, in combination with means for raising and lowering said head. 105

4. In a device of the character stated, a vertically adjustable inverted cup-shaped head, an oppositely apertured tube rotatably mounted therein, arms projecting from the ends of said tube, a transverse rod joining the outer ends of said arms, a vertically adjustable stem having its lower end secured to said rod, a series of curved nozzles secured to said apertured tube, a discharge pipe for leading water into said tube and nozzles and a suction pipe communicating with the upper portion of said head for withdrawing the water and impurities from said head, in combination with means for raising and lowering said head. 115

5. In a device of the character stated, a 130

vertically adjustable, inverted cup shaped head, a transverse tube adjustably mounted in said head and having a lower elongated slot therein, means for discharging water 5 into said tube, a series of curved discharge nozzles fast on said tube in alignment with the lower slot therein, arms extending from the ends of said tube, a transverse rod connecting the ends of said arms and a vertically 10 adjustable stem having its lower end secured to said transverse rod for varying the angular inclination of said discharge nozzles.

6. In a device of the character stated, a 15 vertically adjustable inverted cup shaped head having a bottom outer peripheral upturned flange, a transverse tube adjustably mounted in said head and having a lower elongated slot therein, means for discharging 20 water into said tube, a series of curved discharge nozzles fast on said tube and in alignment with said lower slot, means for withdrawing water from said head, arms rigidly connected to and extending from the 25 ends of said tube, a transverse rod rigidly connecting the ends of said arms, and a vertically adjustable stem having its lower end connected to said rod, for rotatably adjusting said tube and its adjuncts.

30 7. In a filter sand washing machine of the character stated, a floating support, a head adjustably carried by said support and adapted to extend beyond the bottom of said support, there being a chamber formed in 35 said head, a transverse tube rotatably mounted in said head and having a bottom elongated slot therein, a force pump for injecting water into said tube, a series of nozzles fast on said tube and in alignment with 40 said slot, a suction pump for withdrawing water from said chamber, actuating means common to said support and pumps and means for permitting the operation of said pumps simultaneously with, and independently 45 of, said support.

8. In a filter sand washing machine of the character stated, a floating support, a pump shaft thereon, a plurality of pumps actuated by said shaft, a vertically adjustable head 50 carried by said support, a plurality of nozzles movably mounted in said head and adapted to project below the latter into the sand of the filter, a suction pipe for one of said pumps leading from the water to be 55 filtered, a discharge pipe from the same pump leading to said nozzles, and a suction pipe leading from the upper portion of said head to the suction of said other pump, in combination with means for adjusting said 60 nozzles, and means for raising and lowering said head and nozzles simultaneously and independently.

65 9. In a filter sand washing machine of the character stated, a floating support, a pump shaft thereon, a plurality of pumps actuated

by said shaft, a vertically adjustable head carried by said support, a plurality of curved nozzles movably mounted in said head and adapted to project below the latter into the sand of the filter, a suction pipe for one of 70 said pumps leading from the water to be filtered, a discharge pipe from the same pump leading to said nozzles, and a suction pipe leading from the upper portion of said head to the suction of said other pump, in 75 combination with means for adjusting said nozzles, and means for raising and lowering said head and nozzles simultaneously and independently.

10. In a filter sand washing machine, a 80 floating support, vertically disposed guides thereon, an inverted cup-shaped head open at its bottom and closed at its top, positioned between said guides, uprights on said head, rollers on the upper portions of said uprights contacting with said guides, hoisting mechanism for raising and lowering said head, a cross bar carried by said head intermediate of its ends, an adjustable threaded rod passing through said cross bar and the 85 top of said head, a series of adjustable nozzles movably mounted within said head, and connections from the lower end of said adjusting rod to said nozzles for actuating the 90 latter.

11. In a filter sand washing machine, a floating support, vertically disposed guides thereon, an inverted cup-shaped head open at its bottom and closed at its top and carried by said support, rollers on the upper portion of said head bearing on said guides, a hoisting mechanism for raising and lowering said head, a transverse tube rotatably mounted in the lower portion of said head, a series of nozzles secured to said tube and 100 adapted to extend into the sand below the bottom of said head, an adjusting rod extending upwardly through the top of said head, connections from the lower end of said rod to the ends of said tube for rotat- 105 ing the latter, means for injecting clean water into said tube and through said nozzles, and means for withdrawing the used water and impurities accumulating in said head.

115 12. In a device of the character stated, a floating support, vertical guides thereon, an inverted cup-shaped head carried by said support, rollers intermediate said head and guides, means for raising and lowering said head, a series of nozzles rotatably mounted in and adapted to extend below the bottom of said head, means for forcing water through said nozzles, and means for withdrawing water and impurities from said 120 head.

13. In a device of the character stated, a floating support, vertical guides therein, an inverted cup-shaped head carried by said support, rollers intermediate said head and 130

said guides, means for raising and lowering said head, a transverse tube rotatably mounted in the bottom of said head, a series of curved nozzles mounted on said tube and adapted to extend below the bottom of said head, pumping means for forcing water into said tube and nozzles, a suction pump for withdrawing the water and impurities accumulating in said head, and actuating means common to said pumping means and said support, adapted to actuate said pumps simultaneously with or independently of said support.

MORRIS L. BAYARD.
MINOR HARVEY.
